ROCKER LOCK FOR RECLINING PLATFORM ROCKING CHAIR

Ned W. Mizelle, High Point, N.C., assignor to General Steel Products, Inc., a corporation of North Carolina
Filed May 12, 1967, Ser. No. 638,033
4 Claims. (Cl. 297—270)

ABSTRACT OF THE DISCLOSURE

A rocker lock for reclining platform rocking chairs, in which a pair of links pivotally connected substantially end-to-end are pivotally mounted one on a movable seat and the other on the rear of the chair frame, with roller means on one of the links. The links in upright position of the chair are at a large obtuse angle, with the roller high enough that it permits normal rocking. As the chair reclines the seat approaches the rear of the chair frame and the angle of the links closes so as to move the roller onto a back bar of the platform and prevent rocking. With continued reclining the roller moves across the back bar.

Background of the invention

Reclining chairs, in which the seat and back recline and a coordinated leg rest is raised, have become increasingly popular when mounted on a platform rocker base so the chair may be used as a rocker in upright position. However, this requires that means be provided to lock the chair against rocking movement when it is moved to reclining position, because if it is not locked the shift in balance during reclining causes the chair to rock to its maximum rearward position, and this adversely affects the orientation of the chair in reclining position by pitching it too far back.

Several such rocker locks have been devised, some consisting of a fixed arm at each side of the seat with a roller at its lower end, so that lowering of the seat during reclining movement places the rollers on the platform frame to prevent rocking movement; and some consisting of complex linkage systems so that movement of the back or the leg rest locks the chair against rocking.

No such mechanisms heretofore devised have been particularly satisfactory. Those which have stop units on both sides of the chair are almost impossible to align so that both units strike the platform at the same time; and if they do not they place a torsional strain on the arm rest frame. While there have been heretofore some rocker locks having a single unit at the center of the chair, all of them have been characterized by relatively complex and expensive linkages. Some prior art rocker locks have been difficult to adjust so that they would not interfere with normal rocking when the chair is upright.

Summary of the invention

The principal object of the present invention is to provide, for a reclining platform rocking chair, a rocker lock which is simple, inexpensive, effective, easy to install and adjust, and readily arranged so as not to interfere with rocking when the chair is upright.

The objects of the invention are achieved by providing a rocker lock unit as described in the abstract. The rocker lock roller in upright position of the chair is high enough that it cannot interfere with rocking. The use of a pair of folding links to shift the roller downwardly onto the platform frame permits a lock unit to be readily designed to fit any reclining chair mechanism merely by selecting links of the correct lengths.

Rocker locks are most effective on three position chairs, 70

2

i.e., those which recline first to an intermediate position for TV viewing and when may then be moved to a full reclining position. The rocker lock becomes effective when the chair reaches TV position; and the lock of the present invention merely rolls across the back rail as the chair is moved from TV position to full reclining position.

Brief description of the drawings

FIG. 1 is a fragmentary vertical sectional view of a chair embodying the invention, with the reclining mechanism omitted for clarity and the chair in upright position;

FIG. 2 is a rear elevational view of said chair with the rocker lock in the position of FIG. 3;

FIG. 3 is a fragmentary view like FIG. 1 with the chair in an intermediate reclining position; and

FIG. 4 is a view like FIG. 3 with the chair in full reclining position.

Description of the preferred embodiment

Referring to the drawings in greater detail, and referring first to FIGS. 1 and 2, a chair includes a platform, indicated generally at 10, having side frame members 11, a rear cross frame member 12, and a front cross frame member 13. The side frame members 11 have coplanar upper surfaces 14 on which a rocking chair frame, indicated generally at 15, is supported. The chair frame 15 includes a pair of arm members 16 having arcuate bases 17 which rest upon the surfaces 14, a rear crossbar 18 and a front crossbar 19. As is well known in the art, rocker spring units 20 are secured to the side rails 11 and to the arm members 16 to normally retain the chair frame 15 in a predetermined position from which it may rock forwardly and rearwardly.

A seat frame, indicated generally at 21, includes side frame members 22, a rear cross rail 23 and a front cross rail 22a. The seat frame 22 and a back, indicated generally at 24, are supported from the chair frame 15 on any suitable linkage, not shown, which permits the seat and back to move from the upright position of FIG. 1 to a first reclining position as seen in FIG. 3 and to a full reclining position as seen in FIG. 4. A typical linkage which permits such "double" reclining action is disclosed in Mizelle Patent No. 3,269,769, issued Aug. 30, 1966.

The rocker lock of the present invention consists of a linkage, indicated generally at 25, which comprises a long first link 26 which is pivoted at 27 on a bracket 28 on the rear seat rail 23; a short second link 29 which is pivoted at 30 on a bracket 31 on the rear crossbar 18; a pivot 32 which connects the free end 26a of the first link 26 with a point near the free end 29a of second link 29; and a cross pin 33 in the second link 29 between the pivot 32 and the free end 29a of the link 29 which carries roller means 34 consisting of a pair of rollers 34a and 34b (FIG. 2) which flank the links 26 and 29. Although link 26 in the illustrated embodiment is pivoted at 27 to the rear seat rail 23, it will be appreciated that the link could be pivoted to any point on the seat frame, and that rear rail 23 has been selected to minimize the length of the link. Additionally, while the rearmost end of link 26 is shown as being pivoted to an intermediate point on link 29, it could be pivoted to the end of link 29 so as to be coincident with the axis of roller means 34.

In the upright position of FIG. 1 the links 26 and 29 are at a large obtuse angle, with the pin 33 seated in a notch in first link 26, and the roller means 34 above any part of the arcuate surfaces 17 which support the chair upon the platform surfaces 14 so there is no interference with rocking of the chair.

As the chair is moved toward the first reclining position of FIG. 3, which is a comfortable position for TV view-

ing, the seat frame 21 moves linkage 25 rearwardly toward the rear crossbar 18 and folds the links so that the long link 26 swings the short link 29 downwardly and rearwardly about its pivot 30 to a generally vertical position and brings the roller means 34 into contact with a rear plate 12a on the rear cross frame member 12. With the rocker lock linkage in the position of FIG. 3 the seat can no longer be rocked rearwardly.

As the seat frame 21 and back frame 25 are moved to the full reclining position of FIG. 4 the back of the seat moves upwardly as the seat continues to move rearwardly; and the roller means 34 moves slightly rearwardly on the wear plate 12a as arms 16 rock crossbar 18 slightly downwardly so that in full reclining position of the chair the rollers occupy the position of FIG. 4 and the linkage 25 and roller means 34 continue to prevent rocking action of the chair. It will be appreciated that depending upon the specific reclining mechanism that has been selected link 29 and roller means 34 could move forwardly in moving to the full reclining position, but in all instances, the rollers means will remain in engagement with the wear plate 12a to prevent rocking action of the chair.

As the chair is again moved to upright position the linkage is extended by the forward movement of the seat 22, and the roller means 34 returns to the position of FIG. 1 so the chair 15 is free to rock on the platform 10.

The foregoing detailed description is given for clearness of understanding only and no unnecessary limitations should be understood therefrom, as modifications will be obvious to those skilled in the art.

I claim:

1. In a chair which has a platform that includes a rear cross frame member and a chair frame including a rear crossbar member and arm members with means which rock on the platform and in which a seat member and back member are mounted in the frame for movement from an upright position to a reclining position with the seat member moving toward the rear crossbar member during such movement, rocker lock means comprising: a first link pivotally connected to the seat member;

a second link pivotally connected to the rear crossbar member; a pivot connecting the free end of one of said links to the other of said links; and a roller journaled on said other of said links, said links being so related to one another and to the members with which they are connected that the links in upright position of the seat and back members form a large obtuse angle to one another and the roller is a substantial distance above the platform, while movement of the seat member and back member toward reclining position folds the links and causes the roller to rest on the rear cross frame member of the platform at a predetermined point in said movement toward reclining position.

2. The device of claim 1 in which there is a single rocker lock mounted on the longitudinal median plane of the chair.

3. The device of claim 1 in which the relationship of the links to the rock means of the arm members is such that in upright position of the chair the roller is in a plane above any part of the rock means which contact the platform during rocking movement of the chair.

4. The device of claim 1 in which the first link is substantially longer than the second link, and the pivotal connection is at the free end of the first link and near the free end of the second link.
